UNITED STATES PATENT OFFICE.

HENRY C. BARNETTE AND RANTSLEE M. MASSEY, OF BIXBY, OKLAHOMA.

JACK-PLATE.

Patented Nov. 19, 1916.

1,284,985.

Specification of Letters Patent.

Application filed July 27, 1913. Serial No. 247,065.

To all whom it may concern:

Be it known that we, HENRY C. BARNETTE and RANTSLEE M. MASSEY, citizens of the United States, and residents of Bixby, in the county of Tulsa and State of Oklahoma, have invented certain new and useful Improvements in Jack-Plates, of which the following is a specification.

Our invention is an improvement in jack plates, and has for its object to provide a device of the character specified for supporting oil well jacks, wherein the plate consists of two portions, one engaging the base, the axis rod of the jack resting upon the other, the said other plate being adjustable with respect to the first named plate.

In the drawings:

Figure 1 is a side view of the jack in place on the plate;
20 Fig. 2 is a perspective view of the plate;

Fig. 3 is a transverse vertical section.

The present embodiment of the invention is shown in connection with the rod 1 of a jack 2, and the base or jack plate consists of 25 a lower section or bed 3 and an upper section or cradle 4. The lower section or bed is substantially rectangular, having openings 5 at its corners, by means of which it may be secured to a concrete base, and the upper section is pivotally connected to the lower section as indicated at 6.

This upper section has at one side a circular outline, indicated at 7, the said outline being formed on a circle whose center 35 is the pivotal connection 6, and the lower section has a lip 8 which overlies the upper section at its arc shape or circular outline to limit the upward movement of the upper section with respect to the lower section at 40 such point. The upper section or cradle has a bed 9 extending diametrically of the pivotal connection, the said bed being adapted to receive the rod 1 and being of such length that the rod will fit loosely therein.

The bed is closed at its ends, as indicated 45 at 10, by transverse ribs, and the upper section 4 has curved lugs 11 which curve over the rod 1 when it is in place in the bed, to prevent displacement of the rod. The lower section has lugs 12 at its rear, and through 50 these lugs are threaded set screws 13, the set screws engaging the upper section, and it will be evident that by tightening and loosening the set screws the upper section or bed 55 may be turned with respect to the lower section.

In use, the rod 1 of the jack is arranged in the bed, and by means of the set screws the jack and the beam may be lined up correctly.

It will be noticed that the lip 8 is separable from the lower section or bed 3, and is held to the bed by dowel pins and a bolt and nut 14. The pivot pin 6 is integral with the upper section or cradle.

We claim:

A device of the character specified comprising a lower section adapted to be secured to a fixed support, an upper section having a rotatable connection on a vertical axis with the lower section, said upper section having in its upper face a bed extending diametrically of the pivotal connection for engagement by the rod of a jack, means for moving the upper section angularly on the lower section in either direction and for holding said section in adjusted position, the upper section having a portion provided with a circular outline struck on a circle whose center is the pivotal connection, the lower section having a lip overlying the said edge, and set screws at the opposite edge threaded through the lower section and engaging the upper section.

HENRY C. BARNETTE.
